UNITED STATES PATENT OFFICE.

CHARLES D. GERVIN, OF NEW YORK, N. Y., ASSIGNOR TO JOHN H. DALE, OF NEW YORK, N. Y.

SERIES LAMP-RECEPTACLE.

966,681.

Specification of Letters Patent. Patented Aug. 9, 1910.

Application filed February 20, 1909. Serial No. 479,209.

To all whom it may concern:

Be it known that I, CHARLES D. GERVIN, a citizen of the United States, residing at the city of New York, in the borough of Manhattan and State of New York, have invented certain new and useful Improvements in Series Lamp-Receptacles, of which the following is a full, clear, and exact description.

10 My invention relates to series lamp receptacles.

The main object is to provide a convenient and efficient cluster for incandescent lamps connected in a single series circuit.

15 A further object of the invention is to provide a series cluster or lamp receptacle which is removable and interchangeable with others in its attachment upon a fixed support. Reference is made to my co-pending application No. 451,562, in which a 20 multiple cluster for this same object is set forth.

The circuit wires of a building are necessarily more or less permanent fixtures, and in the ordinary practice of inclosing the circuit wires in conduit pipes, it is evident that the protruding pipe or conduit at the location of the various lights, etc., is also a permanent fixture. The general practice 25 has been to connect the desired cluster or lamp receptacle to such conduit pipe and then make the electrical connections from the circuit wires separately. This is obviously troublesome and damages the circuit wires. Whenever a new lamp shade 30 is required, all these connections have to be broken in order to permit the lamp shade to be placed over the receptacle and around the conduit pipe. The connections 35 also have to be entirely broken or remade when a new receptacle is to be substituted for the one in use. By my invention all 40 these difficulties are overcome. I provide the conduit pipe with a permanent receptacle support. This support is small enough 45 to permit an ordinary shade to be slipped over it and is interchangeably adapted to series or multiple, or other receptacles for any desired number of lamps. The 50 mechanical attachment and the electrical connections are all attained by the simple act of pressing the receptacle onto said support.

With the foregoing and other objects in view my invention consists in the features

of construction and combination as hereinafter set forth and claimed. 55

In the drawings: Figure 1 is a plan view of a receptacle embodying the principles of my invention; Fig. 2 is a vertical sectional view of the same attached upon its conduit support; Fig. 3 is a detail partly sectional view showing the method of connecting the different lamps in series, and Fig. 4 is a bottom plan view of the fixed support.

1 denotes an insulating base in the form 65 of a truncated conical ring of porcelain or insulating material.

2 designates threaded shells having lips or flanges 3 at their rear ends which abut against the outside conical face of the base 70 1. Each threaded shell is secured in this relation by an interiorly insulated disk 4 and a bolt 5 which passes through the base 1, causing the lips or flanges 3 to be tightly embraced between the disk 4 and base 1. 75 Each threaded shell has a tongue 6 projecting laterally therefrom. These tongues are most conveniently formed by stamping a strip out of the bottom of a threaded shell having an entirely closed bottom wall, thus 80 leaving on each side a pair of segmental portions of said bottom wall to constitute the lips 3. At the opposite side from the tongue 6 each threaded shell is cut away at 7, and into the recesses thus formed there 85 projects the tongue 6 of the next adjacent shell. (See Fig. 3). The position of the recess 7 is such that the material taken therefrom may be made to constitute an extension of the tongue 6, on the opposite 90 side of the shell, making the length of the tongue somewhat greater than would otherwise be the case. By this means each tongue projects far enough into the next threaded shell to receive the bolt 5 through an opening in its extremity. 95

8 denotes a washer interposed between the head of the bolt 5 and the tongue 6 to make a neater and better connection.

By the foregoing means each threaded 100 shell is provided with a center contact and the different shells and contacts are connected in a single series circuit. While I consider this particular means as the most desirable manner of accomplishing the functions stated, I do not, of course, desire to be limited or restricted thereto. One of the threaded shells 2', is unprovided with a 105

laterally extending tongue 6, but has a radially extending tongue 6', which is joined to a metallic ring 10, by a soldered or other joint at 11. The ring 10 is most conveniently formed of sheet metal stamped into an annular form of U-shaped transverse section. On its lower side the ring has a plurality of extensions or lugs 10' which are fastened to the base 1 by the screws 12. The screws 12 are located at points intermediate the shells 2, so as to avoid any possibility of a short-circuit between the parts of different potential. 14 denotes a plate fixed beneath the center of the ring 10 in any suitable manner, as for example, by an extending side, 14' screwed to the inner face of the base 1 by a screw 5' which is employed as a center contact for the threaded shell adjacent to the shell 2', in place of the bolt regularly employed. 16 denotes a casing of the usual hemispherical or other sort, having holes 16' through which the threaded shells project and in which they are secured by the bushings 17. Any suitable inclosure may be provided to cover the open upper side of the casing 16. The fixed support with which the foregoing receptacle co-operates has been fully shown and described in my companion application above referred to, being designed to operate equally well with a series, or multiple receptacle, or any other kind. It comprises essentially an insulating body 20 with a plurality of depending spring prongs or tongues 21 each having a shoulder 22 to engage them within and beneath the ring 10 of the receptacle. 23 is a longer centrally depending spring prong which extends into contact with the plate 14 when the receptacle is assembled on the prongs 21, as just described. The prong 23 constitutes one terminal of the line circuit and any one or more of the supporting prongs 21 may be made the other terminal. It is evident that the receptacle is mechanically affixed to its support by merely pressing it over the prongs 21 and all the electrical connections are established by the same act. The outside diameter of the support 20 is so small that any ordinary lamp shade passes readily over it, so that the latter may be supplied, or renewed, or removed, whenever desired without any more disturbance than pulling off the receptacle and pushing it back in place again. Also the receptacles themselves are interchangeable by the same simple manipulation, the series receptacle of the present case being replaceable by the multiple receptacle of my prior case, and vice versa, or any other change effected, as desired. The building is conveniently com-

pleted with only the conduit or fixture supports in place, and the tenant can thereafter apply and change around the receptacles to suit his purposes and conveniences.

What I claim is:—

1. A cluster receptacle comprising an insulated base, a plurality of threaded shells secured around the periphery thereof, center contacts, means for connecting said shells and center contacts in a series circuit, a ring 75 and a concentric plate forming the terminals of said circuit, and means adapted to be simply pushed into engagement with said ring and plate for supporting the receptacle and establishing the electrical connections. 80

2. A cluster receptacle comprising a base, a plurality of threaded shells thereon each having a laterally deflected tongue on one side and a recess on its opposite side, and means for retaining said shells in position 85 upon said base, said means comprising center contacts into engagement with which said tongues extend through said recesses.

3. A cluster receptacle comprising a base, a plurality of threaded shells thereon, each 90 of said threaded shells having a tongue stamped integrally therefrom and projecting laterally to one side and having a recess on its opposite side, and means for retaining said shells in position upon said base, 95 said means comprising center contacts into engagement with which said tongues extend through said recesses.

4. A cluster receptacle comprising a base, a plurality of threaded shells thereon, each 100 of said threaded shells having a tongue stamped integrally therefrom and projecting laterally to one side and having a recess on its opposite side, and shell retaining bolts secured to said base and constituting center 105 contacts, said tongues engaging said bolts through said recesses.

5. A cluster receptacle comprising a flat, annular base, a plurality of threaded shells secured around the periphery thereof, said 110 shells having bottoms with a portion stamped outward therefrom to constitute a tongue, said shells having a recess on the opposite side, and center contacts into engagement with which said tongues extend 115 through said recesses.

6. A cluster receptacle comprising an insulating ring, a plurality of threaded shells having lips resting on the outside of said ring, bolts constituting center contacts and clamping said lips to said ring, and a tongue on each threaded shell extending into engagement with the bolt of an adjacent shell. 120

7. A cluster receptacle comprising an insulating base, a plurality of threaded shells 125 having lips resting directly on the outside of said base, center contacts, tongues extending laterally from all but one of said shells and making connection with the center contact of an adjacent shell, and electrical connec- 130

tions from the extreme center contact and threaded shell, respectively, of the series thus established.

8. A cluster receptacle comprising a base, 5 a plurality of threaded shells thereon, tongues extending laterally from said threaded shells, center contacts each engaged by the tongue of an adjacent shell, a metallic ring constituting a terminal, a metallic plate also constituting a terminal, and 10 means for electrically connecting said ring and plate as terminals of the series lamp circuit established as set forth by said tongues.

9. A cluster receptacle comprising a truncated conical insulating ring, a plurality of 15 threaded shells secured on the outside of said ring, each of said shells having a laterally extending tongue, center contacts engaged by the tongue of an adjacent shell, 20 and connecting means, having upwardly disposed portions, secured to said rings for establishing terminal connections for the series circuit thus produced.

10. A cluster receptacle comprising a truncated conical insulating ring, a plurality of 25 threaded shells secured on the outside of

said ring, each of said shells having a laterally extending tongue, center contacts each engaged by the tongue of an adjacent shell, and a plate and a metallic ring secured to 30 said insulating ring, constituting terminals for the series circuit thus produced.

11. A cluster receptacle comprising a truncated conical insulating ring, a plurality of 35 threaded shells secured on the outside of said ring, each of said shells having a laterally extending tongue, center contacts each engaged by the tongue of an adjacent shell, a plate and a metallic ring secured to 40 said insulating ring, constituting terminals for the series circuit thus produced, and means adapted to be simply pushed into engagement with said metallic ring and plate for supporting the receptacle and establishing the electrical connections. 45

In witness whereof, I subscribe my signature, in the presence of two witnesses.

CHARLES D. GERVIN.
